UNITED STATES PATENT OFFICE.

DUDLEY FARRAND, OF NEWARK, NEW JERSEY.

HEATING SYSTEM.

Application filed May 12, 1920. Serial No. 380,731.

To all whom it may concern:

Be it known that I, DUDLEY FARRAND, a citizen of the United States, residing at Newark, in the county of Essex and State of New Jersey, have invented certain new and useful Improvements in Heating Systems; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in heating systems for buildings, etc.; and the present invention has reference, more particularly, to a novel heating system in which is employed one or more gas-heaters in which water is heated, so as to produce vapor, which vapor is drawn by means of a circulating pump, or similar means, after the circulating pump has started, through a system of piping and a 20 radiator or radiators located in said piping, the system comprising also a motor-driven or otherwise suitably operated blower for forcing a supply of air to the gas-burner or burners of the gas-heater or heaters above 25 mentioned.

The present invention, therefore, has for its principal object to provide a novel and simple heating system in which vapor is produced in a usual hot-water gas-heater, such as is ordinarily used in dwellings, the 30 gas-heater being installed in the circulating pipes of the heating system, and in which a constant circulation of vapor is maintained at a very slight expense and at a great saving of fuel, the devices and parts of the 35 system being arranged to operate in a rapid and efficient manner, as soon as the gas is lighted, so that immediately upon the opening of the radiator-valve an immediate and 40 rapid circulation of hot vapor will be produced through the pipe-system and the radiator or radiators located in said system.

Other objects of the present invention not at this time more particularly enumerated 45 will be clearly understood from the following detailed description.

With the various objects of the present invention in view, the said invention consists, primarily, in the novel heating system 50 hereinafter set forth; and the said invention consists, furthermore, in the novel arrange-

ments and combinations of the various devices and instrumentalities comprising and embodying the novel features of the present invention, as well as in the details of the 60 construction of the several parts, all of which will be more fully described in the following specification, and then finally embodied in the clauses of the claim which are appended to and which form an essential 65 part of the said specification.

The invention is diagrammatically illustrated in the accompanying drawing, which shows one embodiment of the present invention.

In the said illustration, the reference-character 1 indicates a suitable storage tank, adapted to be supplied with water from the usual water-supply pipe 2, in which there may be a shut-off cock, as 3. This pipe 2, as shown, leads into the top or upper portion of said tank, and connected with and extending from the bottom or lower portion of the tank 1 is a water-conveying pipe 4, connected with and leading into the side 70 and near the bottom of an ordinary water-heater or heaters, as 5, of the usual household type. Within the water-heater 5 is a coil, as 6, terminating in the side, at or near the upper portion of the heater. Connected with the upper portion of the coil or coils 6, as the case may be, is a main pipe 7 and its branches, as 8, in which are arranged the radiators 11 of any suitable and usual construction. The pipes 7 and 8 75 80 may be provided with the usual shut-off valves, as 9 and 10, substantially as shown.

The reference-character 12 indicates a return-pipe of the main system, and 13 are return-pipes from the radiators to said main 85 return-pipe 12, said return-pipe 12 being connected with the water-conveying pipe 4 90 which is connected with the heater or heaters 5.

In connection with the above described 100 system is employed a suitable arrangement of circulating blower or pump 14, and an air-blower 15, all preferably arranged upon a single shaft 16, upon which is also mounted an electric motor 17, or other suitable prime 105 mover, for operating said shaft 16, the circulating pump 14, located above the normal water-level in the tank 1, and the air-blower 15 mounted upon said shaft. The blower or pump 14 is connected with the main return-pipe 12 by means of a pipe 18 which 110 leads from the return-pipe 12 into the in-

take side of the blower or pump 14, and connecting the discharge end of the said blower or pump with the storage tank 1 is a pipe 19. The previously mentioned 5 heaters 5 may also be connected with the pipe 19 by means of connecting pipes 20 which lead into the upper end-portions of the said water heaters 5, said pipes 20 being preferably provided with suitable shut-off 10 valves, as 21. The said pipes 18, 19 and 20, as will be evident are also located above the normal water-level in the tank 1. Connected with the exhaust or outlet-end of the air-blower 15 is a pipe 22 which leads to 15 the burner or burners 23 of the heater or heaters 5 for forcing air from the blower to said burner or burners to create an increased amount of heat, as will be clearly evident from an inspection of the drawing. The 20 pipe 22 is provided with the usual stop-cocks 24, and 25 is the usual gas-supply pipe in which the burner or burners 23 are arranged, suitable stop-cocks 26 being also placed in the pipe 25.

25 From the foregoing description it will be clearly evident, that a simple and efficiently operating heating system, in which heat is produced by vapor, is the result, said system being especially adapted for use in connection with hot-water heaters or boilers of the usual type ordinarily used in dwellings.

From an inspection of the drawing it will be noticed that the light-pressure blower or pump 14, with its pipes 18 and 19, is located at a point above the normal level $x-x$ of the water within the tank 1, the result being, that when either or both of the burners 23 have been lighted, and the prime mover 17 has been set in motion, any air and water due to condensation, that may be contained in the radiator or radiators, is drawn therefrom into and through the pipes 13 and 12, any condensed water dropping past the pipe 18 into the lower portion of the pipe 12, while the air is drawn into and through the blower or pump 14, forced into the pipe 19, and thence into the upper portion of the tank 1, above the level of the water therein, and also into the upper portion of the heater or heaters 5, for equalizing purposes, to prevent a vacuum both in the tank and the heaters, where this portion of the air is heated and passes through the pipes 7 and 8, co-mingled with the heated vapor from the coils 6, back into the radiator or radiators.

60 Owing to the light pressure of the blower or pump 14, and due to the fact that it is located considerably above the level of the water within the tank 1, any tendency of short-circuiting the water through the pipe 19, the tank 1, the pipe 4 and the lower part of the pipe 12 to the blower or pump is entirely overcome.

65 I am aware that some changes may be

made in the general arrangements and combinations of the various devices and parts, as well as in the details of the construction of the said parts, without departing from the scope of the present invention as set forth in the foregoing specification, and as defined in the clauses of the claim which are appended thereto. Hence, I do not limit my present invention to the exact arrangements and combinations of the several devices and parts as described in the said specification, nor do I confine myself to the exact details of the construction of the said parts, as illustrated in the accompanying drawing.

I claim:—

1. In a vapor system, a hot-water heater, a primary circulating system comprising a conveying riser extending from said heater, a radiator connected with said riser, a water-supplying means connected with and leading to said heater, a return-pipe leading from said radiator, an equalizing pipe between said return-pipe and said water-supplying means, and a circulating pump in said equalizing pipe, said equalizing pipe 80 and said pump being located at a point above the normal level of the water in the heater.

2. In a vapor system, a hot-water heater, a primary circulating system comprising a 95 conveying riser extending from said heater, a radiator connected with said riser, a water-supplying means connected with and leading to said heater, a return-pipe leading from said radiator, an equalizing pipe between said return-pipe and said water-supplying means, and a circulating pump in said equalizing pipe, said equalizing pipe 100 and said pump being located at a point above the normal level of the water in the 105 heater, combined with a gas-supply pipe, a burner in said pipe, said burner being located beneath said water-heater, an air-conveying pipe connected with said burner, and an air-blower in said air-conveying pipe, 110 said circulating pump and said air-blower being mounted upon the same shaft, and an electric motor also mounted upon said shaft for driving the same.

3. In a vapor system, a main water tank, 115 a main water supply-pipe connected with and leading to said main water-tank, a hot-water heater, a water-conveying pipe connecting said main water-tank with said hot-water heater, a primary circulating system 120 comprising a conveying riser extending from said heater, a radiator connected with said riser, a return-pipe connected with and leading from said radiator and connected with the water-supply pipe between said 125 main water-tank and said hot-water heater, an equalizing pipe between said return-pipe and said main water-tank, and a circulating pump in said equalizing pipe, said equalizing pipe 130 and said pump being located at a

point above the normal level of the water in the tank.

4. In a vapor system, a main water-tank, a main water supply-pipe connected with and leading to said main water-tank, a hot-water heater, a water-conveying pipe connecting said main water-tank with said hot-water heater, a primary circulating system comprising a conveying riser extending 10 from said heater, a radiator connected with said riser, a return-pipe connected with and leading from said radiator and connected with the water-supply pipe between said main water-tank and said hot-water heater, 15 an equalizing pipe between said return-pipe and said main water-tank, and a circulating pump in said equalizing pipe, said equalizing pipe and said pump being located at a point above the normal level of the water in the tank, combined with a gas-supply pipe, 20 a burner in said pipe, said burner being located beneath said water-heater, an air-conveying pipe connected with said burner, and an air-blower in said air-conveying pipe, 25 said circulating pump and said air-blower being mounted upon the same shaft, and an electric motor also mounted upon said shaft for driving the same.

In testimony that I claim the invention set forth above I have hereunto set my hand 30 this 6th day of May, 1920.

DUDLEY FARRAND.
